UNITED STATES PATENT OFFICE.

JOHN ROBERTSON MUNN AND GEORGE MACLAREN, OF GLASGOW, SCOTLAND, ASSIGNEES
TO THE BRITISH MARINE MOTOR & LAUNCH COMPANY, LIMITED, OF WHITEINCH,
GLASGOW, SCOTLAND.

COLLAPSIBLE LIFE-BOAT AND THE LIKE.

1,147,966.

Specification of Letters Patent.

Patented July 27, 1915.

Application filed April 29, 1915. Serial No. 24,714.

To all whom it may concern:

Be it known that we, JOHN ROBERTSON MUNN and GEORGE MACLAREN, subjects of the King of the United Kingdom of Great Britain and Ireland, and resident of Glasgow, Scotland, have invented a certain new and useful Improvement in Collapsible Life-Boats and the like, of which the following is a specification.

10 This invention relates to bulwarks for collapsible lifeboats or the like and it consists in a construction comprising substantially plane mid portions adapted to fold inwardly in relation to the boat, and end 15 portions accommodated in said mid portion or portions when the lifeboat is collapsed and slideable endwise relatively thereto when the lifeboat is to be launched, said end portions being of such formation and (or) mate- 20 rial that they may be bent to conform to the contour of the boat, but will not be liable to be formed transversely.

A bulwark embodying the invention is illustrated in the accompanying drawing in 25 which—

Figure 1 is a fore and aft section showing the bulwark extended. Fig. 2 a plan view and Fig. 3 a thwartship section.

Referring to the drawing, 1 denotes the 30 mid portions of the bulwark which are hinged at 2 to fold inwardly as shown in Fig. 3. The mid portions 1 are formed with recesses and grooves to receive the end portions 4, such end portions being slideable in 35 relation to the mid portions so as to form extensions serving to bridge the gaps between the mid portions and the stems 5 of the boat. The said end portions 4 are flexible so that they may be bent to conform to 40 the contour of the boat. The end portions 4

are composed of wood, *e. g.*, of a series of interconnected slats arranged after the fashion of the top of a roll top desk; or sheets of multiple ply veneer may be employed for the same purpose. To insure that the bulwark shall be water-tight, the ends of the 45 said end portions 4 are adapted to enter recesses in the stems 5 which latter are capable of folding inwardly. The upper and the lower edges of the end portions 4 are guided 50 in grooves, the upper edges engaging recesses in movable gunwales 6 and the lower edges engaging recesses in fixed guides 7.

It is to be understood that the invention in its broader aspects is not limited to the 55 precise construction shown nor to any construction by means of which the invention may be carried into effect, since many changes may be made without departure from the essence of the invention as defined 60 by the appended claim.

We claim:

In a collapsible lifeboat or the like, a bulwark comprising, in combination, hinged mid portions and end portions adapted to 65 be accommodated in said mid portions and slideable endwise relatively thereto, said end portions being capable of assuming a curvature in conformity with the contour of the boat, and of resisting stresses tending to deform the same in transverse direction, sub- 70 substantially as described.

In testimony whereof we have signed our names to this specification in the presence of two subscribing witnesses.

JOHN ROBERTSON MUNN.
GEORGE MACLAREN.
